Application November 10, 1951, Serial No. 255,766

3 Claims. (Cl. 332—56)

1

This invention relates to modulators and more particularly to modulators generally of the mechanical type used for course identifying beacons' signals.

Various types of modulators have been provided particularly for applying course identifying signals to radio beacons. In the more usual types of modulators of the known art, the mechanical variety, wherein a motor driven tuning element is used to vary the tuning of networks coupled to transmission lines, has most generally been provided. The network may take the form of a stub connected line or a coupled section of transmission line which in one tuning condition serves substantially to block transmission along the line and in another tuning condition permits energy to be fed through the line to the load, most generally radiating antennas. Instead of utilizing mechanical tuning means switching tubes have been used in such coupled networks for the purpose of providing the desired modulations. However, most of these circuits are not readily adaptable for use with coaxial feed lines and considerable complication in mechanical structure results when coaxial feed is used. The coaxial feed line however provides for better shielding of the feed lines and, therefore, is desirable in many cases.

It is an object of this invention to provide a novel modulator, preferably of the mechanical tuning type, suitable for use with coaxial feeders for supplying energy to radiating loads.

According to the broader aspects of this invention the modulator comprises a two-conductor feed line for coupling a carrier frequency source to a load, the line having provided in one of its conductors a reactor of a given sign, for example an inductor, the other conductor being provided with an arrangement normally providing a high series impedance which may be effectively an open circuit therein. An arrangement is provided for periodically shunting across this high impedance a reactor substantially equal to the given reactance but of opposite sign to provide a series resonance in the feed line so that energy may be periodically transmitted to the antenna at the modulating rate.

According to a feature of this invention the modulator structure may comprise a coaxial line arranged in the form of a substantially U-shaped loop, one of the conductors, preferably the outer conductor, being cut away to provide a gap therein about the bend in the U. A connection is provided between the cut away conductor portions on the legs of the U at points spaced from

5 the gap, preferably at such points that the sections of transmission line together with this interconnection connecting means provide effectively a balanced quarter wave length stub line presenting substantially infinite impedance to transmission of energy along this conductor. The other conductor, preferably the inner conductor, extends beyond the gap to form the bend in the U and provides a series inductance in this conductor of the line. Connected across the 10 end of the conductor portions at the gap is provided a variable reactor having a capacitive value when completely inserted such that a resultant reactance substantially equal to the inductive value of the inductance of the loop in the inner conductor is provided. Thus as the reactor is varied between its fixed limits the 15 transmission line varies in impedance between substantially infinite impedance and a series resonant condition at a rate determined by the rate of variation in the reactor. Preferably the reactor is a rotatable condenser unit driven by a motor so that effectively a sine wave variation may be produced in the radiating load coupled to the modulator.

The above mentioned and other features and objects of this invention and the manner of attaining them will become more apparent and the invention itself will be best understood by reference to the following description of an embodiment of the invention taken in conjunction with the accompanying drawings, in which

20 Fig. 1 is a diagrammatic illustration of a glide path radio beacon incorporating modulators in accordance with this invention.

Fig. 1A is an equivalent circuit diagram of the modulator as illustrated in Fig. 1, and

25 Fig. 2 is an illustration, partly broken away, of structural embodiment of a modulator in accordance with this invention.

30 Turning first to Fig. 1 there is illustrated the essential circuit diagram of a glide path radio beacon which has incorporated therein modulators constructed in accordance with this invention. Energy from a carrier frequency source 1 is fed over a coaxial line section 2 to a modulator bridge arrangement 3 comprising four coaxial line sections 4, 5, 6 and 7 having a characteristic impedance of $\sqrt{2}$ times the generator impedance. Each of arms 4, 5 and 6 are preferably made one quarter wavelength long at the carrier frequency while arm 7 is made three-quarters of a wavelength long so that the carrier frequency energy will substantially cancel out 35 at the junction of arms 6 and 7. At this junc-

ture there may be provided a non-dissipative network 8 which can cancel reactive energy when the loads on the bridge are not exactly balanced. In actual operation complete balance will not at all times be present so this compensating network is effective for a mean condition of unbalance. From juncture of arms 4 and 7 is extended a coaxial feed line 9, folded in the form of a loop, for supplying energy to a first radiator 10. A similar coaxial conductor 11 extends from the juncture of arms 5 and 6 to supply energy to a second radiator 12. In practice antennas 10 and 12 are mounted at different heights above the earth so as to produce overlapping radiating patterns, which patterns are to be modulated with different identifying signals so that the course line may be identified on a craft. In order properly to adjust the relative amplitudes of the energy supplied to the two antennas a variable network 13 is shown coupled to the feed line of antenna 12. This network may be adjusted to control the relative amplitude of energy reaching antenna 12.

In order to provide the desired modulation of the energy radiated from the antenna separate modulating networks 14 and 15 are provided in the feed lines 9 and 11. The modulation network 14 comprises the substantially U-shaped portion of transmission line 9 having two leg portions 16 and 17 and a loop or bend portion 18. The outer conductors of portions 16 and 17 are cut away at one end to provide a gap 19 about the bend portion 18, a short circuiting bar 20 is provided to interconnect leg portions 16 and 17 at a point spaced from the gap 19 in the outer conductor. Bridged between the outer conductors 16 and 17 at the gap is provided a variable reactor 21 which may comprise a pair of stator plates 22, 23 and a rotor plate 24. The rotor plate 24 may be in the form of a multiple bladed wheel or disc which is driven at predetermined rate by means of a motor 25 so that the blades are intermittently inserted between the stator plates 22 and 23. The modulator 15 associated with transmission line 11 is similar in all respects to modulator 14 except that the tuning reactor 26 thereof is provided with a rotor having a different number of tuning blades so that when it is driven by motor 25 in synchronism with rotor 24 a different frequency, due to variation in reactor tuning, will be produced. Thus modulator 14 may produce the 90 cycle signal generally used in radio beacon work, while modulator 15 produces 150 cycles.

The operation of the modulator to produce the modulation signals may be more clearly understood from the explanation which follows. Preferably the transmission line network is designed to present the desired effective impedance to the carrier source to match the impedance thereof. The line 2 is of such a length that the carrier source 1 may be considered effectively to be located at the juncture of arms 4 and 7 and at the juncture of lines 5 and 6. The portions of lines 9 and 11 between these respective junctures, and the respective gaps should be an integral multiple of one-half wavelength at the operating frequency so that effectively the generator source may be considered as being located at the gap. Since the outer conductor is severed at this point there will be presented to the source a relatively high impedance. The inner conductor forms a loop 18 at this point so across the gap in the outer conductors there exists a voltage difference, which voltage difference will tend

to produce in legs 16 and 17 a transmission of a balanced line nature. The shorting bar 20 if located at a quarter wavelength from the gap will render the portions of the outer conductors in the form of the quarter wave section of balanced transmission line. Under these conditions a high impedance, substantially infinite, will exist between the outer conductors at the gap. Thus there is a discontinuity in the feed line to the antenna which substantially interrupts transmission thereto. This is the condition of minimum energy transfer in the modulation cycle.

The loop 18 formed by the center conductor represents a certain value of inductive reactance. If a capacitive reactance is placed between the outer conductors at the gap which permits a resultant reactance of equal value to loop 18, a series resonant condition will be produced in the feed line resulting in a low impedance across the gap. This will restore continuity in the conductors so that power is transmitted to the antenna. Thus by periodically introducing and removing such a reactance, modulation of energy supplied to the antenna can be produced. Since the voltages on the outer conductors at the gap are of equal amplitude and opposite polarity it will be apparent that in the plane mid-way between the outer conductors there exists an equi-potential region. A conductor can, therefore, be introduced along this equi-potential plane without having any appreciable voltage induced in it. Thus the multi-bladed rotor may be inserted at this point of equi-potential for varying the capacity between these points. It will be clear, therefore, that by rotating such multi-bladed rotor at a desired speed a modulation of the required frequency can be produced. The shaping of the stator and rotor blades is made so as to produce effectively sine wave modulation with minimum distortion.

In the modulator 15 the rotor may be provided with five blades while that in modulator 14 has three blades so that the rotation of these two blades by the motor 25 will produce the desired 90 and 150 cycle modulation. Preferably the rotor and stator blades for the 150 cycle modulator are made smaller than those of the 90 cycle modulator. This is done so as to provide less energy at antenna 12 than at 10 to achieve the desired glide path energy distribution. An additional control may be effected by network 13.

It will be realized that there is a certain minimum capacity between the stators in reactors 21 and 26 so that corresponding shorting bars are not spaced exactly at a quarter wavelength but are varied from that to take care of this capacitive end effect. If less than 100% modulation is desired the corresponding shorting bars may be moved so as to make the effective stub sections longer than a quarter wavelength so that the impedance at the minimum transfer position is reduced permitting some energy to reach the antennas during these points of the modulation cycle. In this way the adjustment of the shorting bars can be used to control the percentage modulation of the tone frequencies.

In the simplified equivalent circuit diagram of Fig. 1A the fundamental operation of the system can be easily seen. In this figure the source 1 is shown supplying energy to the two conductors 27 and 28 of a two-conductor feed line interconnecting source 1 with a load 29. In one of these conductors is provided an inductor 30 and in the other of the conductors is provided a gap 31 bridged by a shorted stub 32. Across the

gap 31 is provided a capacitive reactor 33 which may be adjusted to provide series resonance in the line in the manner described above. It will be apparent that while in the preferred form of the invention the gap is produced in the outer of the conductors, the system will operate if the gap is provided in the inner conductor together with the variable reactor there-across for compensating the inductance produced by the outer conductor.

In Fig. 2 is shown an actual structural arrangement for the modulators 14 and 15 shown diagrammatically in Fig. 1. In this figure a box or trough 34 is provided within which the legs 16, 17 of the modulator U-loop are mounted. These conductors may be supported by insulating supports 36 and 37. A pair of metallic elements 38, 39 are clamped by means of a screw 40 to the outer conductors of legs 16 and 17 to provide the effective shorting bar 19. The inner conductors 41, 42 are interconnected at their ends by a conductor block 43 to produce the U bend 18. At the gap ends of conductor legs 16 and 17 are provided mounting clamps 44 and 45 which serve to support the separate stator plates 22 and 23. The multi-bladed rotor 24 is shown mounted in a box portion 46 of a cover plate 47 so that the blades may be rotated in the central plane between stators 22 and 23, by means of drive shaft 48.

While this invention has been described specifically with reference to a glide path beacon modulator circuit it will be clear that the modulators may be used with any type of system desired. They may, for example, be used to produce monitoring modulations or may be used for localiser or other types of beacons as well. Likewise, the specific structural arrangement may be readily modified as will be apparent to those skilled in the art.

While we have described above the principles of our invention in connection with specific apparatus, it is to be clearly understood that this description is made only by way of example and not as a limitation to the scope of our invention as set forth in the objects thereof and in the accompanying claims.

What is claimed is:

1. A modulator structure comprising a coaxial transmission line arranged in the form of a substantially U-shaped loop, the outer conductor of said line being cut away to provide a gap

therein around the bend in said U, the inner conductor forming a U-shaped loop outside said gap, means interconnecting the conductor portions of said outer conductor in the legs of said U at points spaced from said gap, a variable capacitor coupled between said portions of said outer conductor substantially at said gap, and terminal connections at the ends of said legs for connecting a carrier frequency supplied and a load, respectively thereto.

2. A modulator structure according to claim 1, wherein said means interconnecting said conductor portions is electrically spaced substantially a quarter wavelength at said carrier frequency from said gap.

3. A modulator comprising two coaxial line sections each having inner and outer conductors and being positioned parallel to one another and with one of their ends in alignment, the outer conductors being removed for substantially equal distances adjacent said one end, means for connecting together the inner conductors of said lines at said aligned ends, whereby an effective series inductive impedance is provided in said line, a conductive connection interconnecting the outer conductor of said line sections to provide effectively a quarter wavelength balanced line stub between the point of said interconnection and the ends of said outer conductor to produce effective high series impedance in said line and means for periodically introducing a capacitive reactance between the outer conductors at said one end to produce a series tuning of said line whereby carrier energy supplied to one of said coaxial line sections will be periodically modulated at the output of the other of said line sections.
